US00D784288S

(12) **United States Design Patent** (10) **Patent No.:** **US D784,288 S**
(45) **Date of Patent:** **** Apr. 18, 2017**

(54) **AMPLIFIER**

- (71) Applicant: **QSC, LLC**, Costa Mesa, CA (US)
(72) Inventor: **Douglas William Teulie**, Huntington Beach, CA (US)
(73) Assignee: **QSC, LLC**, Costa Mesa, CA (US)
(**) Term: **15 Years**
(21) Appl. No.: **29/560,736**
(22) Filed: **Apr. 8, 2016**

Related U.S. Application Data

- (63) Continuation of application No. 29/508,895, filed on Nov. 12, 2014, now Pat. No. Des. 754,096, which is a continuation of application No. 29/452,632, filed on Apr. 18, 2013, now Pat. No. Des. 719,128.

(57) **CLAIM**

I claim the ornamental design for an amplifier, as shown and described.

DESCRIPTION

FIG. 1 is a front isometric view of a first embodiment of the amplifier showing my new design.

FIG. 2 is a front elevation view of the first embodiment.

FIG. 3 is a back elevation views of the first embodiment.

FIG. 4 is a top plan view of the first embodiment.

FIG. 5 is a bottom plan view of the first embodiment.

FIG. 6 is a left side elevation view of the first embodiment.

FIG. 7 is a right side elevation view of the first embodiment.

FIG. 8 is a front isometric view of a second embodiment of the amplifier showing my new design.

FIG. 9 is a front elevation view of the second embodiment.

FIG. 10 is a back elevation views of the second embodiment.

FIG. 11 is a top plan view of the second embodiment.

FIG. 12 is a bottom plan view of the second embodiment.

FIG. 13 is a left side elevation view of the second embodiment; and,

FIG. 14 is a right side elevation view of the second embodiment.

Any broken lines shown in the drawings are for illustrative purposes only and form no part of the claimed design.

1 Claim, 14 Drawing Sheets
